UNITED STATES PATENT OFFICE

149,759

DESIGN FOR A SHOE

Guenther G. Kasket and Margot Kasket,
New York, N. Y.

Application February 1, 1947, Serial No. 136,606

Term of patent 3½ years

(Cl. D7—7)

To all whom it may concern:

Be it known that we, Guenther G. Kasket and Margot Kasket, both citizens of the United States, residing in New York, in the county of New York and State of New York, have invented a new, original, and ornamental Design for a Shoe, of which the following is a specification, reference being had to the accompanying drawing, forming part thereof.

In the drawing, the figure is a side perspective view of a shoe, showing our new design, the opposite side presenting substantially the same appearance as the side shown, except for the buckle.

We claim:

The ornamental design for a shoe, as shown and described.

GUENTHER G. KASKET.
MARGOT KASKET.
